CLAIM

The ornamental design for a display screen or portion thereof with animated graphical user interface, as shown and described.

DESCRIPTION

FIG. 1 shows a first image of a display screen or portion thereof with animated graphical user interface showing our claimed design; and,

FIG. 2 shows a second image thereof. The peripheral dashed broken lines illustrate a display screen or portion thereof and the remaining broken lines illustrate portions of the animated graphical user interface. None of the broken lines form part of the claimed design. The appearance of the graphical user interface transitions between images shown in FIGS. 1-2. The process or period in which one image transitions to another forms no part of the claimed design.
